UNITED STATES PATENT OFFICE.

PAOLO MOLINARI, OF TARANTO, ITALY.

DRIVING MECHANISM FOR MOTORS AND ROTARY PISTON PUMPS.

Application filed August 25, 1923. Serial No. 659,302.

To all whom it may concern:

Be it known that I, PAOLO MOLINARI, a subject of the King of Italy, and residing at 42 Via de Cesare, Taranto, Italy, have invented certain new and useful Improvements in Driving Mechanism for Motors and Rotary Piston Pumps, of which the following is a specification.

The invention relates to improvements in driving mechanism for motors and rotary piston pumps.

The invention will hereafter be described with reference to a pump, but it is evident that it might equally well be applied to motors if the driving fluid is made to enter through the delivery pipes and is discharged through the suction pipes, or vice versa.

In the drawings which refer to a small hand-driven pump of a capacity of about 2500 tons per hours,—

Figure 1 shows on the left hand side a sectional elevation on line B—B of Figure 2 and on the right hand side an outside view of the pump,

Figure 2 is a sectional plan view on line A—A of Figure 1,

Figure 3 is an outside view of the cover plate with the boss member,

Figure 4 is a sectional elevation thereof.

The pump comprises a circular dish-shaped plate 1 which at its center forms a hub with a tapered bore for the passage of the driving shaft 2. In Figure 1 the driving shaft is shown as having a square upper end to attach thereto a hand-wheel for the operation of the pump, but it is evident that it might also have a cylindrical upper end for connecting it with a motor or the like. The plate 1 is rigidly connected to shaft 2 by means of a key 3, a nut 4 engaging a threaded portion of the shaft and held in place by a stop pin, and a clamping ring 5 lodged between the circular plate and a shoulder at the lower end of the shaft.

The circular plate 1 has secured to it by means of countersunk screws 6 a cylinder 7 provided on its inner surface with teeth. These teeth are interrupted by three large teeth 8 spaced apart by 120° and hereafter referred to as suction and delivery teeth. On the top of the gear cylinder 7 is secured by countersunk screws a ring 9.

The circular plate 1, the gear cylinder 7 and the ring 9 are assembled to form one single unit and in pumps of larger dimen-

sions they may be held together by tap bolts or studs.

Within the gear cylinder 7 are arranged two pinions 10 which revolve on stationary spindles 11, these spindles being square-shaped at their lower end and projecting from the respective pinion. Each pinion is provided with a semi-cylindrical recess to receive the suction and delivery teeth 8 as will hereafter be explained.

The whole device is covered by a cover plate 12 which is traversed centrally by the driving shaft 2. Formed integrally with this cover plate is a downwardly projecting ring-shaped hollow boss member 13, on whose outer cylindrical wall the ring 9 and the suction and delivery teeth 8 are arranged to slide. This boss 13 is provided with two semi-cylindrical recesses adapted to accommodate the pinions 10.

The hollow boss 13 is divided into four chambers, two 14, 14' for suction purposes and two 15, 15' for delivery purposes, and each of these chambers communicates with a nozzle on the cover plate to which are attached the respective pipes. Each chamber is put in communication with the sector-shaped hollows formed between the gear cylinder 7 and the sliding surface of the boss 13, by means of three tapered square-shaped ports provided in the sliding surface adjacent the pinions, these ports being indicated by 16, 16', 16'', 16''' in the drawing.

The square-shaped lower ends of the spindles 11 are seated in a circular plate 17 embedded in the plate 1 and secured by means of countersunk screws to the boss member 13, whereas their upper cylindrical ends are seated in the cover plate 12.

The plate 17 serves also as a cover for the suction and delivery chambers and as a division between these chambers. The whole device is enclosed within an outer casing 18 secured to the cover plate 12 by means of bolts or set screws and provided with lugs for securing the pump to a support.

The ring 9 is formed with an upwardly projecting rim 19 which engages a circular groove provided in the cover 12, for the purpose of affording an additional security against leakages between the ring 9 and the boss member 13. In a like manner a downwardly extending circular projection 20 is provided on the plate 17 and engages a

groove formed in the plate 1 to assist in preventing leakages between the plates 1 and 17. The pinions 10 are closely fitted between the cover 12, the ring 9 and the plate 17 as well as in the semi-cylindrical recesses of the boss members 13 and their teeth engage the gear cylinder 7 so as to provide for the formation of the sector-shaped hollows. The inner circumference of the gear cylinder 7 is three times as large as the circumference of the pinions 10 so that during each revolution of the gear cylinder the pinions will complete three revolutions. The suction and delivery teeth and the recesses within the pinions are shaped so that during the rotation of the gear cylinder the tooth adjacent the recess in the pinion remains for a short period in contact with the respective suction and delivery tooth, in order to prevent leakages between the hollows when the pinions are no longer in engagement with the smaller teeth of the gear cylinder. However, the teeth of the gear cylinder which are arranged symmetrically respecting the suction and delivery teeth, might also extend close up to the flanks of these large teeth, so that at the entrance of these teeth into the recess of the pinions the teeth of these pinions will always be in mesh with the teeth of the gear cylinder.

The pump works as follows:

During the rotation of the driving shaft 2 and of the gear cylinder 7 in the direction of the arrow (Fig. 2) the suction and delivery teeth which slide on one side a sucking action and thus cause liquid to flow through the ports into the cylindrical hollows, while on the other side they produce a compression of the liquid sucked up by the preceding tooth so as to cause the liquid being driven into the respective delivery pipe. During the rotation of the gear cylinder 7 a rotary motion is imparted to the pinions 10 through the teeth of these two parts being in mesh, and the arrangement is such that the pinions will complete their revolution and their recess be brought opposite the gear cylinder when the suction and delivery teeth are approaching the pinions.

To provide for the discharge of the liquid caught in the space between the suction and delivery teeth and the pinions at the moment when these teeth are closing the ports and are about to enter the respective recess in the pinions, there are provided grooves 22 on the wall of the recess in the boss 13 towards the ports and small holes 23 are provided at the end of the edge of the recess in pinions 10, these holes and grooves being shaped and arranged so that there remains a sufficient clearance between them and the edges of the suction and de-

livery teeth. The holes might be replaced by grooves formed on the projecting edges of the recesses in the pinions.

In order to permit the escape of any liquid that may be caught between the teeth of the pinions and those of the gear cylinder 7, these pinions are slightly tapered, as indicated in 24, along a line whose length is almost equal to the depth of the teeth, and this taper corresponds to a like taper in the semi-cylindrical recesses of the boss member 13.

To avoid a suction and a delivery chamber being put in communication through a sector-shaped hollow, the suction and delivery teeth and the ports are so dimensioned that when a tooth is about to uncover the delivery port of a hollow the successive tooth will already have covered the corresponding suction part.

In motors and pumps which must deliver at a high pressure, blade springs 25 and plates 26 may be arranged inside each suction and delivery tooth to assure the required contact between the teeth and the wall of the boss member 13. The length of the springs is equal to the width of the teeth, while the plates 26 project slightly at one end into the ring 9 and at the other end into the plate 1, whereby displacements of these plates are prevented during the passage of the suction and delivery teeth through the recesses in the pinions.

In pumps which work at a high pressure it is advisable to balance at least partly the pressure to which the pinions are subjected in the semi-cylindrical recesses in the boss member 13 and for this purpose small clearances 27, 27' may be provided which by means of channels 28, 28' communicate with the delivery chambers. The pump may thus rotate in either direction and the suction and delivery actions be inverted.

Instead of projecting through the cover 12 the shaft 2 might also be made to pass through the casing 18, in which case the taper of the hub would of course be inverted.

In the case of pumps of large dimensions the boss member 13 may be formed separately and be secured to the cover 12 by means of studs and nuts and in this case the plate 17 may be cast in one piece with the boss member 13.

The central wall of the boss member 13 around the driving shaft, the suction and delivery chambers and the outside wall of the gear cylinder may be provided with collars of zinc or the like and with protective plates in case the pump is to work with salt water. Ball bearings may be arranged both on the driving shaft and beneath the circular plate 1 and the spindles of the pinions may be drilled centrally to permit lubrication by means of lubricators arranged on the cover.

Further, in the case of pumps working at a high pressure, in order to keep the plate 1 balanced, holes may be provided therein opposite the plate 17 so that the pressure eventually set up between the plates will be balanced by the pressure between the plate 1 and the casing.

What I claim is:

1. In a driving means for motors or rotary piston pumps, a driving shaft, a gear operated thereby, suction and delivery teeth formed on the gear, a hollow boss having a cylindrical surface for cooperation with the suction and delivery teeth, springs and plates carried by said suction and delivery teeth to prevent leakage between said teeth and the sliding surface, the hollow boss member being formed with two suction and two delivery chambers communicating with sector-shaped hollows formed between the gear cylinder and the sliding surface of the boss, and connections between said hollows and delivery chambers to permit reverse action of the pump.
2. In a driving means for motors or rotary piston pumps, a driving shaft, a gear operated thereby, suction and delivery teeth formed on the gear, a hollow boss having a cylindrical surface for cooperation with the suction and delivery teeth, springs and plates carried by said suction and delivery teeth to prevent leakage between said teeth and the sliding surface, the hollow boss member being formed with two suction and two delivery chambers communicating with sector-shaped hollows formed between the gear cylinder and the sliding surface of the boss.

piston pumps, a driving shaft, a gear operated thereby, suction and delivery teeth formed on the gear, a hollow boss having a cylindrical surface for cooperation with the suction and delivery teeth, springs and plates carried by said suction and delivery teeth to prevent leakage between said teeth and the sliding surface, the hollow boss member being formed with two suction and two delivery chambers communicating with sector-shaped hollows formed between the gear cylinder and the sliding surface of the boss, and connections between said hollows and delivery chambers to permit reverse action of the pump.

In testimony whereof I have signed at Messina this 6th day of August, 1923, in the presence of two subscribing witnesses.

PAOLO MOLINARI.
